UNITED STATES PATENT OFFICE.

ALFRED C. HOBBS, OF BRIDGEPORT, CONNECTICUT, ASSIGNOR TO THE UNION METALLIC CARTRIDGE COMPANY, OF SAME PLACE.

BULLET-PATCHING MACHINE.

SPECIFICATION forming part of Letters Patent No. 257,584, dated May 9, 1882.

Application filed February 15, 1882. (No model.)

To all whom it may concern:

Be it known that I, ALFRED C. HOBBS, of Bridgeport, Connecticut, have invented certain Improvements in Devices for Automatic-ally Feeding Bullets to Bullet-Patching Ma-chines, of which the following is a specifica-tion.

My improvement relates to the feeding of bullets by an endwise movement to that class of bullet-patching machines in which bullets deposited in recesses in the periphery of a continuously-rotating horizontal disk are rolled along the concave face of a stationary guard-wall, and enwrap their lower portions with a slip of paper which they pick up as they are successively rolled across the exterior of a mass of such slips contained in a magazine inserted in and forming a part of the said guard-wall. A method of feeding bullets to this class of machines by a bodily sidewise move-ment of the bullet is described in the pending application of Alfred C. Hobbs, Theodore V. Boyden, and Charles R. Richards, filed Feb-ruary 9, 1882.

In my present invention I employ the ordinary friction dial feed, by which the bullets, resting upon their bases, are gradually brought into column and pushed forward and delivered successively to a continuously-rotating trans-fer-wheel, which in some respects is similar 35 in its construction to the hooked transfer-wheel shown and described in the said applica-tion of Messrs. Hobbs, Boyden, and Rich-ards, but differs therefrom in respect of its 40 location with relation to the patching-machine disk. Instead of being in the same plane, the transfer-wheel is in a slightly higher plane, and its edge overlaps the edge of the patcher-disk. The transfer-wheel and the patcher-disk are so geared together that the speed 45 with which the recess in the periphery of the patcher-disk moves through the arc of a circle under the transfer-wheel is uniform with the speed with which the bullet is moved through the reverse arc of a circle in the plane 50 above the patcher-disk. A bullet caught side-ways and carried around by one of the teeth or hooks of the transfer-wheel is supported upon its base upon a stationary table or bed beneath the transfer-wheel until it arrives at a point

immediately over one of the recesses in the patcher-disk, where the table ends, and the bullet, pushed off the curved edge of the table at that point, is permitted to drop by an end-wise movement downward into the recess in 55 the patcher-disk.

The accompanying drawings, representing a bullet-patching machine containing my im-provement, are as follows:

Figure 1 is a top view. Fig. 2 is a top view, 60 upon an enlarged scale, of a portion of the patching-machine disk and the overlapping portion of the transfer-wheel; and Fig. 3 is a vertical section through the line *x x* on Fig. 1, a portion of this line being also shown in Fig. 65 2, in which it is indicated by the letters *y y*.

As the patching-machine to which my device is applied is fully described in the pending application of Hugo Borchardt, filed February 10, 1882, and is also shown in the pending ap-plication of Messrs. Hobbs, Boyden, and Rich-ards, before referred to, no special description of it is necessary herein. For the purpose of the present case it will be sufficient to say that the patching-machine disk A has the recesses 75 *a* formed in its periphery and is continuously rotated.

The bullets, resting upon their bases upon the surface of the ordinary friction feed-dial, B, are by means of the guide-walls *b b* ar-ranged in single column and thrust succes-sively against the periphery of the transfer-wheel C, provided with the ratchet-teeth *c*, the face of each of which and the immediately adjoining portion of the periphery of the trans-fer-wheel present the semicircular recess *c'*, 85 in which the body of the bullet rests and from which it is prevented from dislodgment dur-ing its transfer by the exterior guard-wall, D. On reference to Fig. 2 it will be seen that the bullet E, deposited in the recess *c'*, is pre-vented from tipping forward out of that re-cess by the exterior guard-wall, D.

The spring F (shown on a large scale on Fig. 2) is one of several similar springs shown in 95 Fig. 1, each of which extends through a horizontal slot in the guard-wall and bears upon the periphery of the transfer-wheel. These springs may be employed, if desired; but they do not form a part of my present invention, 100

and are not essential when the transfer-wheel is constructed, as shown, in such a manner that the space between the guard-wall and the periphery of the transfer-wheel at the forward edge of the recess c' is less than the transverse diameter of the bullet. The base of the bullet, while being carried around by the transfer-wheel, rests upon the stationary table or bed G , beneath the transfer-wheel, 5 and upon an extension, g , of this bed, which projects a short distance over the edge of the patcher-disk A . The extension g affords a support upon which the base of the bullet rests until, by the rotation of the transfer-wheel and 10 of the patcher-disk, one of the recesses a in the patcher-disk is brought immediately under the bullet, in position to receive the bullet as it drops, after having been pushed off the curved edge g' of the extension g . During the 15 time occupied by the bullet in dropping from the transfer-wheel to the recess in the patcher-disk the bullet is preserved in the necessary upright position by the semicircular recess c' and the guard-wall D .

20 It will of course be understood that instead of depending upon gravity for the endwise movement of the bullet from the transfer-wheel into the recess in the patcher-disk, a positively-acting device may be employed to 25 thrust the bullet endwise in the proper direction. Such a device, however, will not be necessary unless the transfer-wheel and the patcher-disk should be made of unusually small diameter.

30 It will also be understood that instead of the continuously-rotating transfer-wheel a reciprocating carrier or pusher may be employed to push the bullets successively from the end of the column delivered by the friction-dial, along 35 a path extending over the edge of the patcher-

disk, in a direction nearly coincident with the arc of the circle described by a recess in the patcher-disk during the time required to enable the bullet to move from the pusher into the recess.

45

I claim as my invention—

1. The herein-described method of feeding bullets into the recesses formed in the periphery of the continuously-rotating patcher-disk A , which consists in imparting, by means of a 50 suitably-moving carrier or pusher, a sidewise movement to the bullet in a plane overlapping the face of the patcher-disk while the bullet is passing by an endwise movement into one of the said recesses in the periphery of the 55 continuously-rotating disk.

2. The friction feed-dial B , provided with the guide-walls b , and the transfer-wheel C , provided upon its periphery with the ratchet-teeth c and the recesses c' , in combination with 60 the table or bed G , g and the guard-wall D , substantially as set forth.

3. The friction feed-dial B , provided with the guide-walls b , the transfer-wheel C , provided upon its periphery with the ratchet-teeth c and the recesses c' , the table or bed G , g , and the guard-wall D , in combination with 65 the patcher-disk A , provided with the recesses a in its periphery, whereby bullets arranged in column by the friction feed mechanism are 70 deposited successively in the recesses c' of the transfer-wheel and carried along the table G and over the edge of the extension g and delivered endwise into the recesses a in the periphery of the patcher-disk A .

A. C. HOBBS.
